UNITED STATES PATENT OFFICE.

MORTON I. DORFAN, OF NEW YORK, N. Y., ASSIGNOR TO ALLIS-CHALMERS MANUFACTURING COMPANY, OF MILWAUKEE, WISCONSIN, A CORPORATION OF DELAWARE.

APPARATUS FOR TREATING FUMES.

Application filed November 21, 1923. Serial No. 676,018.

This invention relates in general to improvements in the art of treating gases, and relates more specifically to an improved process of and apparatus for collecting and subsequently treating the gases or fumes generated at several sources such as a plurality of retort furnaces, in order to recover from the fumes one or more of the constituents.

A general object of the invention is to provide an improved process of collecting and of separating the constituents of gases or fumes derived from a plurality of sources. Another general object of the invention is to provide simple and efficient apparatus for effecting commercial exploitation of the improved process.

In the treatment of zinc and other ores for the recovery of metals, it is common practice to utilize a plurality of similar retorts located in close proximity to each other, wherein the ore is confined while being heated. During operation of these retort furnaces, and while the ore is being converted, combustible gases are being delivered from the condensers associated with each of the retorts. The combustible gases thus discharged are ignited in the presence of air producing a flame the character of which indicates the condition of the ore within the retort. The fumes produced by combustion of the gases contain a considerable quantity of metal particles which are carried in mechanical suspension and also contain other solids. These solid laden fumes are ordinarily delivered from the smelter and are eventually deposited upon the land adjoining the smelter plant, such deposit of the solid particles being extremely objectionable due to the fact that they are destructive to vegetation. As the combustion of the gases escaping from the retorts and normal access to the retorts and condensers must not be interfered with, and also because of the fact that separation of the solids from the gases in the presence of an abundance of excess air is relatively costly, it has heretofore been commercially impracticable to remove the solids from the fumes.

The present invention contemplates provision of an improved process of removing the solids from the fumes delivered from a plurality of retort furnaces, and of effectively recovering the valuable constituents at relatively low commercial cost. With the aid of the present improved process and appara-

tus, the fumes may be refined without interfering with the normal operation of the apparatus which produces the substance subjected to treatment. With the improved apparatus, manipulation of retort furnaces is greatly facilitated by virtue of the fact that the products of combustion are immediately discharged from the furnace room thereby avoiding excessive radiation of heat to the working space in front of the retorts. The improved apparatus is entirely automatic in operation and comprises generally the provision of means for collecting the fumes generated at each of a plurality of sources in the presence of a limited quantity of excess air, means for subsequently cooling the mixture of air and fumes while conducting this mixture from the place of origin, and means for subsequently separating the constituents of the fumes. With the aid of the improved apparatus the volume of the mixture of fumes and air is reduced to a minimum thereby enabling the use of a separator having relatively small capacity and minimizing the commercial cost of separation. The foregoing as well as other objects and advantages of the present invention will be apparent in the course of the accompanying description.

A clear conception of the several steps of the improved process and of the details of construction and operation of one form of apparatus embodying the present invention may be had by referring to the drawings accompanying and forming a part of this specification, in which like reference characters designate the same or similar parts in the several views.

Fig. 1 is a fragmentary vertical section through a multiple retort smelting furnace, showing a fume collecting hood associated with each of the retort gas discharge openings, and also showing conducting and cooling means for conveying the accumulated fumes to a dust collector.

Fig. 2 is a fragmentary horizontal view through a multiple retort smelting furnace, showing a plan view of several fume collecting hoods and the fume conducting means associated therewith.

Fig. 3 is an enlarged fragmentary vertical section through several retort furnaces and improved apparatus for collecting the fumes generated thereby.

Fig. 4 is an enlarged fragmentary horizon-

tal section through several retort furnaces and improved apparatus for collecting the fumes generated thereby.

Fig. 5 is an enlarged fragmentary front elevation of one of the fume collecting conduits or ducts, showing details of construction of the improved apparatus.

While the invention will be described herein as specifically applied to the art of smelting zinc in retort smelting furnaces, it is not intended to limit the scope of the invention by such specific disclosure. It will be obvious that the principles of the invention are more generally applicable to a process of and 15 apparatus for collecting and subsequently treating gases or fumes derived from various sources, the separation of constituents not necessarily being limited to a separation of the solids from the gases.

20 The retort furnace comprises in general a plurality of cylindrical retorts 2 located closely adjacent to each other and having their external surfaces exposed to a heating zone 3 wherein intense heat is maintained in 25 any convenient manner. The lower extremity of each of the retorts 2 is provided with a condenser 4 having a discharge orifice 5 through which combustible gases are normally delivered from the interior of the retorts 2. The discharge orifices 5 are accessible from the furnace manipulating room wherein is located a railway 6 upon which a car 7 is transportable. The car 7 carries a ladle 8 and other apparatus for charging and 35 otherwise manipulating the retorts 2.

A fume collecting hood is located above the gas discharge orifices 5 of each pair of laterally adjacent retort condensers 4, each hood comprising a stationary top plate 9, a pivoted 40 rear plate 10, and a pivoted front plate 11. The rear and front plates 10, 11 are supported from front and rear edges of the top plate 9 by means of hinges 13 and are capable of being swung into various positions of 45 adjustment and of being retained in such positions by means of sliding bolts 16, 20, 22, 23. The top plates 9 are secured to supporting brackets 21 which are rigidly attached to the furnace structure 12, and are located directly 50 above the flames produced by ignition of the gases escaping from the orifices 5, see Figs. 3 and 4. The rear plate 10 of each hood is provided with cut out portions 19 which are adapted to partially embrace the 55 adjacent condensers 4 when the rear plate 10 is lowered. The rear bolts 20 are adapted to retain the rear plates 10 in upper position under certain conditions of operation of the apparatus, see Fig. 3. The front plate 11 60 of each hood is provided with cut out portions 18 which permit free inspection of the condensers 4 and provide sight openings for viewing the condition of the flames at the discharge orifices 5 of the condensers 4 when 65 the front plate 11 is lowered. The upper

front bolts 16 are adapted to retain the front plate 11 in its uppermost position under certain conditions of operation of the apparatus; the intermediate front bolts 22 are adapted to retain the front plate 11 in an intermediate position of adjustment under other conditions of operation; while the lower front bolts 23 are adapted to retain the front plates 11 in normal lowered position. The hood plates 9, 10, 11 may be formed of special heat resisting material and form a pocket through the lower extremity of which only sufficient air is admissible to support proper combustion of the gases delivered from the orifices 5.

Each of the fume collecting hoods communicates through an orifice with a fume duct 14 which is common to a plurality of the hoods. The orifices which provide means of communication between the hoods and the fume ducts 14, are preferably controllable by means of dampers 15 adjustable with the aid of handles 17, in order to control the volume of the mixture of fumes and air produced within each of the hoods. The fume ducts 14 communicate with piping 24 leading to a gas cooler 25 of any approved form. The gas cooler 25 communicates with a separator 26 which in the present instance preferably consists of a fabric bag type dust collector, but which may be any form of separator adapted to separate the constituents of the gas mixture delivered from the cooler 25. The flow of the gases through the ducts 14, piping 24, cooler 25 and separator 26 may be produced by means of a fan the suction of which is connected to the discharge of the separator in a well known manner.

During normal operation of the retort furnace, the retorts 2 are charged with ore, reducing agent and other substances from the car 7 after which the discharge orifices 5 are closed sufficiently to maintain only a relatively small discharge opening. The retorts are then subjected to heat from the heating zone 3 and combustible gases are driven off through the orifices 5 and are ignited. The hoods which serve to collect the fumes resulting from such ignition and combustion of the gases are then arranged as illustrated in the upper portion of Fig. 3 whereupon excess air is admitted from below to the interior of the hoods and mixes with the fumes, the mixture being delivered past the damper 15 to the fume duct 14. The mixtures of fumes and excess air entering the fume duct 14 travel through the conducting pipes 24 to the cooler 25 wherein the temperature of the mixture is substantially reduced. From the cooler 25 the combined mixture of fumes and air passes through the separator 26 wherein the gases contained in the mixture are withdrawn through fabric bags while the solids are accumulated upon the surfaces of the bags and are periodically removed. The solids thus

removed from the gases are either returned to the retorts 2 during charging of the latter, or may be otherwise treated to recover valuable constituents thereof.

- 5 When it is desired to inspect the condenser 4 of a retort 2 as when drawing off some of the molten metal, without removing the retort, the front cover 11 of the retort to be inspected may be positioned with the aid of the 10 intermediate front bolt 22 as shown in the lower portion of Fig. 3. With the front plate 11 of the hood thus positioned, the discharge orifices 5 of the condensers 4 delivering into the hood are freely accessible, and the hood 15 remains effective to collect fumes discharged from the retorts 2. When it is desired to recharge or to remove a retort 2 with its condenser 4, both the rear plate 10 and the front plate 11 may be positioned as illustrated at 20 the intermediate portion of Fig. 3, the rear plate 10 being held in its upper position by means of the bolts 20, and the front plate 11 being retained in its upper position by the upper front bolts 16. With the hood plates 25 thus positioned, the retorts 2 associated therewith may be freely removed. It will thus be noted that the adjustability of the hood plates 10, 11 permits unobstructed manipulation of the retort furnace for all conditions of operation.

The damper 15 and the relatively small inlet opening for excess air communicating with each hood, permit accurate control of the volume of the mixture of fumes and air thereby 35 enabling the use of cooling and dust collecting apparatus of minimum capacity. It may of course be desirable to provide a bottom plate for each hood if it is found that the quantity of excess air is greater than that desired or 40 if the distribution of the air to the hoods is inefficient. Besides enabling control of the quantity of excess air which is mixed with the fumes, it will be obvious that the front plates 11 serve as shielding aprons which will protect the furnace attendants against radiation of excessive heat from the flames. While the cut out portions 18 may be left open in most cases, it will be obvious that these cut out portions 45 may be provided with transparent medium such as mica without departing from the spirit of the present invention.

It will thus be noted that with the improved process of collecting and of treating the fumes, the solid constituents may be effectively recovered in a separator of minimum size and at minimum commercial cost, without in any manner interfering with the normal operation of the retort furnace. Manipulation of the retort furnace is greatly facilitated by 55 the shielding action of the hoods and the proportion of air mixed with the fumes may be conveniently varied. The apparatus is entirely automatic in its normal operation and may be installed in a great number of existing furnaces of this general type. While each of the

hoods of the present disclosure serves to collect the fumes from two retorts, it will be obvious that each hood may serve only one retort, or may even be made to serve any limited number of retorts greater than one.

It should be understood that it is not desired to limit the present invention to the exact steps of the process or to the exact details of construction of the apparatus herein shown and described, for various modifications within the scope of the claims may occur to persons skilled in the art.

It is claimed and desired to secure by Letters Patent:

1. In combination with a plurality of retorts each having means for discharging burning fumes, a hood disposed over each of said discharge means, each of said hoods comprising an adjustable wall located in front of said discharge means and being formed to provide a combustion zone at the adjacent retort and having an opening for admitting fresh air directly to said zone, means for collecting gases of combustion from all of said hoods, and means for separating the solids from the collected gases.

2. In combination with a plurality of retorts each having means for discharging burning fumes, a hood disposed over each of said discharge means, each of said hoods comprising a movable wall located in front of said discharge means and being formed to provide a combustion zone at the adjacent retort and having an opening for admitting fresh air directly to said zone, means for controlling the quantity of air admitted to each of said hoods, means for collecting the gases of combustion discharged from all of said hoods, and means for removing the solids from said gases.

3. In combination with a plurality of retorts each having means for discharging burning fumes, a hood comprising removable walls disposed at each of said discharge means, each of said hoods providing a combustion zone at each of said retorts and being formed to admit sufficient fresh air directly to said zone to support complete combustion of the fumes delivered from the adjacent retort, means for collecting the gases of combustion discharged from all of said hoods, means for cooling said gases, and means for removing the solids from said gases.

4. In combination with a plurality of retorts each having means for discharging burning fumes, a hood associated with each of said fume discharge means for collecting gases in the presence of sufficient air to support complete combustion of the discharged fumes, each of said hoods comprising removable walls for permitting access to the adjacent retort, and means for collecting gases of combustion discharged from all of said hoods and for separating the solids therefrom.

5. In combination with a plurality of re-

torts each having means for discharging gases, a hood associated with each of said gas discharge means for collecting gases in the presence of a limited quantity of air, each of said hoods comprising pivoted front and rear plates removable to permit free access to the adjacent retort, and means for collecting the

mixtures of gas and air accumulated in each of said hoods and for separating the solids from said mixtures.
